CLAIM

The ornamental design for an aircraft cockpit window, as shown and described.

DESCRIPTION

FIG. 1 is a perspective view of a top, front, left side of an aircraft cockpit window according to our new design shown on an aircraft shown in broken lines;

FIG. 2 is a left elevation view thereof;

FIG. 3 is a right elevation view thereof;

FIG. 4 is a top plan view thereof; and,

FIG. 5 is a front elevation view thereof.

The broken line showing of the airplane and the window dividers represent unclaimed portions of the aircraft cockpit window and form no part of the claimed design.

1 Claim, 5 Drawing Sheets
